UNITED STATES PATENT OFFICE

ALBERT J. KRUSE, OF FREDERICKSBURG, TEXAS

BALING PRESS

Application filed October 4, 1930. Serial No. 486,429.

This invention relates to baling presses, and it is an object of the invention to provide a device of this kind which can be either manually operated or power operated.

5 It is also an object of the invention to provide a device of this kind embodying a reciprocating plunger together with means whereby said plunger may at will be rendered inoperative at any point of its stroke and which 10 is particularly desirable in the event of accident.

The invention consists in the details of construction and in the combination and arrangement of the several parts of my improved baling press whereby certain important advantages are attained and the device rendered simpler, less expensive and otherwise more convenient and advantageous for use, as will be hereinafter more fully set 20 forth.

The novel features of my invention will hereinafter be definitely claimed.

In order that my invention may be the better understood, I will now proceed to describe the same with reference to the accompanying drawings, wherein:—

Figure 1 is a view in side elevation of a baling press constructed in accordance with an embodiment of my invention;

30 Figure 2 is a view in top plan of the device as herein disclosed;

Figure 3 is an enlarged fragmentary view partly in section and partly in elevation illustrating in detail the mounting of one of the 35 bale holding dogs;

Figure 4 is a longitudinal vertical sectional view taken through the device as herein disclosed with certain of the parts in elevation;

40 Figure 5 is an enlarged fragmentary view partly in vertical section and partly in elevation illustrating the mounting of the end lever together with the parts associated therewith;

45 Figure 6 is a fragmentary view in bottom plan of the rock arm for normally maintaining the plunger in operative engagement with the power wheel.

50 As disclosed in the accompanying drawings, B denotes a baling chamber disposed on a gradual slope from front to back to re-

duce friction of the bale as it passes therethrough, and the forward end portion of the chamber B in its top is provided with a conventional feeding opening 1. The rear or discharge end of the chamber B is adapted 55 to be closed by the swinging door D held in closed position by a latch 3 coacting with an outstanding arm 4 carried by the door D. The side walls 5 at the forward end of the chamber B are provided with elongated slots 60 6 through which work the horizontally swinging dogs 7 to prevent retrograde movement of a follower F under the opening 1 or in a forward direction with respect to the chamber B.

65 Each of the dogs 7 has an angular portion 8 at one end pivotally held by the bearings 9 secured to the outer face of a side wall 5 of the chamber B, and said portion 8 has an intermediate offset part or crank 10 with which 70 engages a spring pressed arm 11 whereby the dog is normally maintained projected within the chamber B yet may be forced outwardly therefrom to permit the rearward passage of a follower F and the hay or kindred material 75 being compressed by the plunger P.

75 The bottom 12 of the chamber B is continued a desired distance in advance of the open forward or front end of the chamber and, as herein disclosed, said extended portion of the bottom 12 is supported by a sill 14. The plunger P is of a reciprocating type and travels over and along the bottom 12 of the chamber B and is provided in its side marginal portions with the slots 14' to permit 80 the plunger to readily pass the portions of the dogs 7 projected within the chamber B upon travel of the plunger P in either direction. To further facilitate the proper entry of the plunger P within the compression portion 85 of the chamber B, a roller 15 is rotatably supported between the side walls of the chamber B in the upper part thereof and immediately adjacent to the inner or rear margin 90 of the opening 1.

95 The plunger P has extending outwardly from its side faces the trunnions 16 upon which are mounted the rollers 17, said rollers working within the longitudinally disposed 100

slots 18 provided in the lower portions of the side walls of the chamber B.

By this means the desired movement of the plunger P is readily controlled yet at the same time allowing the plunger P to have swinging movement with the stub shafts as fulcrums to compensate for the desired action of the operating means for the plunger and such other mechanism associated therewith.

The plunger P has extending forwardly therefrom an elongated member or beam 19, said member or beam 19 and plunger P constituting a rigid structure with the member or beam arranged centrally of the plunger P. The member or beam 19 has its outer portion bifurcated and at opposite sides of the kerf 20 the member or beam 19 is provided in its upper face with the racks 21 with which engage the oppositely and laterally directed trunnions 22 carried by a wheel 23. The trunnions 22 have mounted thereon anti-friction sleeves 24 and the wheel 23 is rotatably mounted upon a supporting shaft 25 carried by and bridging the space between a pair of upstanding posts 26 anchored to the sill 14. The trunnions 22 are arranged in a partial circular series and are of a number sufficient upon a single rotation of the wheel 23 to force the plunger P inwardly of the baling chamber B and at the same time permitting the desired return stroke of the plunger P. This return stroke is accomplished by a retractile member 27 of requisite tension and herein disclosed as a coil spring, having one end suitably anchored to the lower portion of the plunger P and its opposite end portion suitably anchored to the outer end portion of the sill 14.

It is believed to be obvious that as the plunger P is forced inwardly this retractile member or spring 27 is placed under tension so that as the end trunnion 22 leaves the member or beam 19 upon its compression stroke, the plunger P will immediately return to a position in advance of the opening 1. Upon continued rotation of the plunger P hay or kindred material is effectively baled in a well known manner within the chamber B.

The member or beam 19 is normally maintained in a raised or elevated position for proper engagement of the trunnions 22 with the racks 21 through the instrumentality of a vertically swinging rock arm 28 rotatably supported, as at 29, upon the sill 14. The upper or free end portion of this arm 28 is continued by a cross member 30 underlying the beam or member 19 and carrying an anti-friction sleeve or roller 31 which has direct contact with said member or beam 19 from below. The pivoted end portion of the arm 28 is continued by a stub shaft 32 through which is fixed an upstanding rock arm 33. The upper portion of this arm 33 is connected by a retractile member 34, herein disclosed as a coil spring, with a lever 35. This lever 35 is nor-

mally disposed in a vertical direction and has its lower end portion pivotally connected, as at 36, with a side wall of the chamber B and with its upper portion engaged within the holding or retaining member 37 carried by the forward end of the chamber B. With the lever locked in the position just described the retractile member or spring 34 serves to maintain the anti-friction sleeve or roller 31 in effective engagement from below with the beam or member 19, but upon disengagement of the lever 35 from its holding member 37 the rock arm 33 will become ineffective and the member or beam 19 will drop sufficient to disengage the racks 21 from the trunnions 22.

The wheel 23 works within the kerf 20 of the member or beam 19 and at its periphery is provided therealong with the teeth 38 with which is adapted to engage a gravity pawl 39 pivotally connected, as at 40, with a hand lever 41. The hand lever 41 at its lower portion is provided with the arms 42 provided at their free ends with the sleeves or collars 43 freely mounted upon the opposite end portions of the hubs 44 of the wheel 23. As the hand lever 41 is oscillated the wheel 23 will be manually driven to effect the desired compression stroke of the plunger P. Retrograde movement of the wheel 23 is prevented by a holding dog 45 pivotally mounted, as at 46, and engaging by gravity the teeth 38 of the wheel 23. Rotatably supported by a side wall of the device adjacent the wheel 23 is a shaft 47 provided with a rock arm 48 adapted, upon rotation or rocking movement of the shaft 47 in one direction, to contact from above with the member or beam 19 so that the member or beam 19 may be thrown out of operative engagement with the wheel 23 at any time during the movement of the plunger P and which is of especial importance or advantage in case of accident. The shaft 47 at its outer portion is provided with an elongated operating lever 49 which may be readily grasped and manipulated by an individual. The rock arm 48 is normally maintained in position out of contact with the member or beam 19 by a resilient holding arm 50 extending outwardly from a side wall of the device and upon which the lever 49 rests from above. In case of emergency it is only necessary that this lever 49 be pressed downwardly, the resiliency of the arm 50 readily permitting such operation.

The side walls of the chamber B at their forward ends are continued by the horizontally disposed frame members 51 which are also suitably connected to the upstanding posts 26. These frame members 51 are provided with bearings 52 for the parallel shafts 53 and 54, one of said shafts, as herein disclosed, carrying a pulley 55 whereby the same may be readily coupled with a suitable source of power. The second shaft 54 carries the spaced gears 56 and 57 and upon proper ad-

justment of said shaft 54 the gear 56 is brought into mesh with the peripheral teeth of the wheel 23 while the gear 57 is brought into mesh with a gear 58 carried by the shaft 53. By this means the plunger P may be power driven.

If preferred, the pulley may be attached directly to the shaft 54 and in which event the shaft 53 is unnecessary but by use of these two shafts with their associated gearing, desired speed reduction may be readily obtained.

The upper end portion of one of the posts 26 pivotally supports a U-shaped latch member 59 for coaction with one of the arms 42 of the hand lever 41 to hold said hand lever in substantially a vertical position when not in use. This latch, of course, can be readily thrown into inoperative position when desired.

As is particularly illustrated in Figure 4 it is to be noted that the trunnions 22 are substantially in a spiral arrangement with the high or outermost trunnion first engaging the member or beam 19 to force the plunger P inwardly. By this particular arrangement of the trunnions 22 the power imposed upon the plunger P is increased and at the times such increase is required.

Inwardly of the frame members 51 are the supplemental horizontally disposed frame members 60 each being of a length, as illustrated in Figures 1 and 2, to extend beyond the outer end of the members 51. These members 60 are arranged at opposite sides of the wheel 23 and below the hub thereof and coact with the side marginal portions 61 (Figure 5) to limit the upward movement of the member or beam 19 of the plunger P on its back or returned stroke so that the plunger will not interfere with any of the parts of the device.

The outer or extended end portion of each of these members 60 carries a depending latch bar 62 with which is adapted to engage an upstanding catch 63 carried by a side face of the member or beam 19 of the plunger P as illustrated in Figure 1 of the drawings.

The plunger P, under power, passes into the feed chamber of the press as far as required to compress the hay or the like to the desired density. As hereinbefore described, the plunger P is automatically released and by means of the coil spring 27 it is pulled backward. Upon its return the plunger P will strike the wheel 23 with sufficient force to permit a rebound of the plunger P to re-enter the feed chamber of the press a distance sufficient to obstruct, in a measure, the delivery of the hay or the like into the feed chamber. However, by provision of the bars 62 and catches 63, upon this return of the plunger P the engagement of the catches 63 with the bars 62 will prevent such rebound. As the trunnions 22 engage the racks 21, the

catches 63 will be released from the latch bars 62, thus permitting the desired working stroke of the plunger P.

From the foregoing description it is thought to be obvious that a baling press constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. The combination with the baling chamber of a press having a feed opening in communication therewith; of a reciprocating plunger coacting with said chamber, an outstanding elongated member carried by the plunger, a rotatable member, means for rotating said member, coacting means carried by the rotatable member and the elongated member of the plunger for moving the plunger on its compression stroke, automatic means for retracting the plunger, and means for making the second named means inoperative.

2. The combination with the baling chamber of a press having a feed opening in communication therewith; of a reciprocating plunger working in said chamber, an elongated member carried by the plunger, a rotatable member having laterally disposed parts, the elongated member having a rack with which said parts engage upon rotation of the rotatable member for moving the plunger on its compression stroke, means for normally maintaining the rack of the elongated member in a position for mesh with the lateral parts of the rotatable member, and means for maintaining said rack out of engagement with said parts.

3. The combination with the baling chamber of a press having a feed opening in communication therewith; of a reciprocating plunger working in said chamber, an elongated member carried by the plunger, a rotatable member having laterally disposed parts, the elongated member having a rack with which said parts engage upon rotation of the rotatable member for moving the plunger on its compression stroke, a rock arm for contact with the elongated member of the plunger for maintaining said elongated member in proper position in mesh with the lateral parts of the rotatable member, and means for constantly urging said rock arm to maintain the normal position of the elongated member of the plunger.

4. The combination with the baling chamber of a press having a feed opening in com-

munication therewith; of a reciprocating plunger working in said chamber, an elongated member carried by the plunger, a rotatable member having laterally disposed parts, the elongated member having a rack with which said parts engage upon rotation of the rotatable member for moving the plunger on its compression stroke, a rock arm for contact with the elongated member of the plunger for maintaining said elongated member in proper position in mesh with the lateral parts of the rotatable member, a second rock arm movable with the first named rock arm, a pivotally supported lever, a retractile member connecting the second rock arm and the lever, and means for normally holding the lever against movement.

5. The combination with the baling chamber of a press having a feed opening in communication therewith; of a reciprocating plunger working in said chamber, an elongated member carried by the plunger, a rotatable member having laterally disposed parts, the elongated member having a rack with which said parts engage upon rotation of the rotatable member for moving the plunger on its compression stroke, a rock arm for contact with the elongated member of the plunger for maintaining said elongated member in proper position in mesh with the lateral parts of the rotatable member, and means for throwing the elongated member of the plunger in a position free of the rotatable member.

56 6. The combination with the baling chamber of a press having a feed opening in communication therewith; of a reciprocating plunger coacting with said chamber, an outstanding elongated member carried by the plunger, a rotatable member, means for rotating said member, coacting means carried by the rotatable member and the elongated member of the plunger for moving the plunger on its compression stroke, automatic means for retracting the plunger, a rotatable member within the chamber with which the plunger contacts, and means for holding said elongated member in a position for engagement with said coacting means or out of engagement therewith.

7. The combination with the baling chamber of a press having a feed opening in communication therewith; of a reciprocating plunger coacting with said chamber, an outstanding elongated member carried by the plunger, a rotatable member, means for rotating said member, coacting means carried by the rotatable member and the elongated member of the plunger for moving the plunger on its compression stroke, automatic means for retracting the plunger, said baling chamber having side walls provided with elongated slots, and the plunger having outstanding parts extending within the slots to guide the plunger to permit the same to have

rocking movement, and means for holding said elongated member in a position for engagement with said coacting means or out of engagement therewith.

8. The combination with the baling chamber of a press having a feed opening in communication therewith; of a reciprocating plunger coacting with said chamber, an outstanding elongated member carried by the plunger, a rotatable member, means for rotating said member, coacting means carried by the rotatable member and the elongated member of the plunger for moving the plunger on its compression stroke, automatic means for retracting the plunger, and means for holding the plunger from rebounding after completing its return stroke.

9. The combination with the baling chamber of a press having a feed opening in communication therewith; of a reciprocating plunger coacting with said chamber, an outstanding elongated member carried by the plunger, a rotatable member, means for rotating said member, coacting means carried by the rotatable member and the elongated member of the plunger for moving the plunger on its compression stroke, automatic means for retracting the plunger, means for holding the plunger from rebounding after completing its return stroke, said coacting means carried by the rotatable member and the elongated member of the plunger freeing said holding means to permit the plunger to move on its compression stroke.

10. The combination with the baling chamber of a press having a feed opening in communication therewith; of a reciprocating plunger coacting with said chamber, an outstanding elongated member carried by the plunger, a rotatable member, means for rotating said member, coacting means carried by the rotatable member and the elongated member of the plunger for moving the plunger on its compression stroke, automatic means for retracting the plunger, yielding holding dogs normally extending within the chamber, and releasable manually controlled means for maintaining said elongated member in a position for movement by said coacting means.

In testimony whereof I hereunto affix my signature.

ALBERT J. KRUSE.
